UNITED STATES PATENT OFFICE

2,577,259

PENCIL CALENDAR

John Millington, Valparaiso, Nebr.

Application September 23, 1949, Serial No. 117,415

1 Claim. (Cl. 40—108)

1

The present invention relates to pencil calendars and it consists in the combinations, constructions and arrangements of parts herein described and claimed.

Generally there is provided a pencil calendar comprising an elongated hollow cylindrical member to one end of which is inserted a wooden pencil and into the other end of which may be used for storing a paper roll. Rotatably mounted upon the cylindrical member is a barrel having a plurality of spirally arranged openings through which indicia carried by the cylindrical member may be selectively viewed. Adjacent the first mentioned barrel and likewise revolvably mounted upon the cylindrical member is a month-indicating barrel and likewise mounted upon the cylindrical member and adjacent to the month-indicating barrel is a day-of-the-week indicating barrel. Next in order is frictionally mounted an eraser carrying barrel of the device, this providing a pencil, accessible note paper, and an eraser together with a calendar which may quickly and easily be manipulated by the fingers of the user to indicate the month, day-of-the-month and day-of-the-week.

It is accordingly an object of the invention to provide a combination pencil, paper storing device, eraser and calendar.

Another object of the invention is the provision, in a device of the character set forth, of novel means for indicating the date.

A further object of the invention is the provision of a device of the character set forth which is simple in construction, inexpensive to manufacture, easy to operate and yet effective and efficient in use.

Other and further objects of the invention will become apparent from a reading of the following specification taken in conjunction with the drawing, in which:

Figure 1 is a side elevational view of an embodiment of the invention.

Figure 2 is a view similar to Figure 1 but partly broken away to show details of construction.

Figure 3 is an exploded perspective view of a plurality of barrels forming a part of the invention,

Figure 4 is a perspective view of an elongated hollow cylindrical member forming a part of the invention, and

Figure 5 is a sectional view taken along line 5—5 of Figure 1.

Referring more particularly to the drawing, there is shown therein an elongated hollow cylind-

2

rical member 10 having a slightly enlarged portion 11 at one end thereof in which is affixed a hollow cylindrical socket 12 having an annular ridge 13 therein whereby the inward movement of the socket 12 is limited. A pencil 14 of the wooden body type is adapted to be frictionally mounted in the socket 12.

Rotatably mounted upon the elongated cylindrical member or body 10 adjacent the enlarged portion 11 thereof is a barrel 15 having a plurality of spirally arranged openings 16 formed therein.

Imprinted or otherwise carried upon the body 10 for selective display through the openings 16 is a series of day-of-the-month indicating indicia 17. Rotatably mounted upon the body 10 adjacent the barrel 15 is a month-indicating barrel 18 having all of the months of the year indicated on the periphery thereof and, likewise rotatably mounted upon the body 10 and adjacent the barrel 18 is a day-of-the-week indicating barrel 19 having the days of the week indicated on the periphery thereof.

Frictionally mounted upon the end of the body 10 opposite to the enlarged portions 11 and abutting the barrel 19, is a hollow cylindrical eraser holder 20 having an eraser 21 affixed in the outer ends thereof. A roll of paper 22 is adapted to be stored within the body 10 and is accessible at the eraser carrying end thereof.

In operation, it will be apparent that the barrel 15 may be rotated until the proper indicia 17 is displayed through one of the openings 16 and that thereafter the barrel 18 may likewise be revolved until the proper month is shown next to the selected day-of-the-month. After this action takes place, the barrel 19 may be rotated until the proper day of the week is indicated next to the selected month and day of the month indicia heretofore selected. Thereupon the eraser holder

20 may be forced inwardly upon the body to thereby press against the barrel 19 and consequently the barrels 18 and 15 which, in turn, will bear against the enlarged portion 11 to thus retain the barrels 15, 18 and 19 in the preselected alignment. The use of the pencil 14 and the eraser 21 is thought to be obvious but it will be apparent that as note paper is needed, the roll 22 thereof may be removed from the body 10 and portions thereof torn away for use. If desired, the year date may be indicated upon the periphery of the member 20, as indicated at 23.

While but one form of the invention has been shown and described herein, it will be readily apparent to those skilled in the art that many minor modifications may be made without departing

from the spirit of the invention or the scope of the appended claim.

What is claimed is:

A calendar structure of the character described comprising an elongated cylindrical body, a pair of sleeves on the body, one of said sleeves projecting beyond one end of the cylindrical body to form a utility receiving socket in cooperation with the cylindrical body, the other sleeve being formed with a plurality of longitudinally spaced openings spirally arranged around the circumference of the sleeve, said cylindrical body being provided with three circumferential rows of numerals with which the openings are registrable, one row at a time, the socket forming sleeve being provided with indicia representing a particular year, a barrel located on the cylindrical body adjacent the socket forming sleeve and inwardly

thereof and having indicia thereon representing the days of the week and a second barrel on the cylindrical body provided with indicia representing the months of the year, said barrels and sleeve having the openings therein being snugly but rotatably disposed on said cylindrical body.

JOHN MILLINGTON.
